CLAIM

The ornamental design for a chemical dispenser, as shown and described.

DESCRIPTION

FIG. 1 is a perspective view of a chemical dispenser showing my new design;

FIG. 2 is a front elevational view thereof, on an enlarged scale;

FIG. 3 is a rear elevational view thereof, on an enlarged scale; and,

FIG. 4 is a side elevational view thereof, the opposite side, top plan and bottom plan views being identical.

FIG. 1

FIG. 2

FIG. 3

FIG. 4
